SOUND WAVE CATCHER

Filed Nov. 19, 1927

FIG. 1.

FIG. 3.

FIG. 2.

FIG. 4.

Inventor:

Walter Campbell
By Monroe Miller
Attorney

UNITED STATES PATENT OFFICE.

WALTER CAMPBELL, OF SALEM, VIRGINIA.

SOUND-WAVE CATCHER.

Application filed November 19, 1927. Serial No. 234,405.

The present invention relates to sound wave catchers or ear trumpets, and aims to provide a simple and inexpensive sound wave catcher to be applied to the ear so as 5 to facilitate hearing.

Another object of the invention is the provision of such a device which may be folded so as to be carried in the vest pocket or other small space.

10 With the foregoing and other objects in view, which will be apparent as the description proceeds, the invention resides in the construction and arrangement of parts, as hereinafter described and claimed, it being 15 understood that changes can be made within the scope of what is claimed, without departing from the spirit of the invention.

The invention is illustrated in the accompanying drawing, wherein—

20 Figure 1 is a front view of the sound wave catcher as applied to the ear.

Fig. 2 is a top view thereof.

Fig. 3 is an inside elevation of the device.

25 Fig. 4 is an elevation of the ribs or bows folded together, the flexible membrane being omitted for purpose of clearness.

The device comprises a holding frame composed of the ribs or bows 7 and 8 which may be of resilient wire or other suitable 30 stock, and the terminals thereof are hingedly connected, as at 9, thereby permitting the bows to be swung relatively to one another for folding and unfolding the device.

35 A membrane 10 of suitable fabric or other flexible material is attached to the bows 7 and 8 to be folded and unfolded therewith.

The bow 7 is of a shape to serve as a clasp to embrace the ear from in rear, as seen in Figs. 1 and 2, thereby supporting the device

conveniently from the ear, and when the 40 device is unfolded or opened, it provides a forwardly opening cup or trumpet to catch the sound waves and conduct same to the ear, thereby improving the hearing of the wearer. The device, when applied, resembles the use 45 of the hand when cupped behind and outside of the ear, for the same purpose, it being the practice of persons afflicted with partial deafness to cup the hands behind the outside of the ears to catch the sound waves. The 50 present device is convenient, being readily applied to and removed from the ear, and when the device is removed it may be folded flat so as to be readily carried in the vest pocket, purse or other small enclosure. 55

The bows 8 may be of various sizes and forms according to the size and shape of cup or trumpet desired, and the device may be inexpensively manufactured.

Having thus described the invention, what 60 is claimed as new is:—

1. A foldable sound wave catcher having a portion to embrace the ear.

2. A foldable sound wave catcher having a clasp bow to embrace the ear.

3. A foldable sound wave catcher adapted 65 to be applied to the ear.

4. A sound wave catcher comprising hingedly connected bows and a membrane attached thereto.

5. A sound wave catcher comprising hingedly connected bows and a membrane attached thereto, one of the bows being 70 adapted to embrace the ear.

In testimony whereof I hereunto affix my 75 signature.

WALTER CAMPBELL.
